Des. 227,909
Patented July 24, 1973

227,909

ENCLOSURE FOR TRANSFORMERS AND OTHER ELECTRICAL UTILITY APPARATUS

Roy Griffing, 485 N. State Highway,
Lake Arrowhead, Calif. 92352

Filed May 28, 1971, Ser. No. 148,298

Term of patent 14 years

Int. Cl. D13—02

U.S. Cl. D26—15

FIG. 1.

FIG. 2.

FIG. 3.

FIG. 4.

FIG. 1 is an isometric view of an enclosure for transformers and other electrical utility apparatus, embodying my new design;

FIG. 2 is an end elevational view thereof;

FIG. 3 is a side elevational view thereof; and

FIG. 4 is a bottom plan view thereof.

The side not shown in FIG. 3 is identical to the side shown therein. The end not shown in FIG. 2 is identical to the end shown therein.

I claim:

The ornamental design for an enclosure for transformers and other electrical utility apparatus, substantially as shown and described.
